FINGER RING

Joseph Nolen, Kaneohe, Hawaii
(1139A E. Wilson, Glendale, Calif.)

Filed Oct. 23, 1962, Ser. No. 72,230

Term of patent 14 years

(Cl. D45—10)

FIG-1

FIG-2

FIG-4

FIG-3

FIG-6

FIG-5

FIG-7

FIGURE 1 is a perspective view of a finger ring showing my new design;

FIGURE 2 is a front elevational view of the same;

FIGURE 3 is a bottom plan view of the same;

FIGURE 4 is an elevational view of the same as seen from the left in FIGURE 1;

FIGURE 5 is a side elevational view of the same as seen from the right in FIGURE 6;

FIGURE 6 is an elevational view of the same as seen from the right in FIGURE 1; and

FIGURE 7 is a perspective view of the same rotated substantially 90° from the position shown in FIGURE 1.

I claim:

The ornamental design for a finger ring, as shown.
